ATTORNEY

UNITED STATES PATENT OFFICE.

ROBERT W. SCHULTZ, OF CINCINNATI, OHIO.

SPARK-PLUG.

1,267,597.

Specification of Letters Patent. Patented May 28, 1918.

Application filed June 24, 1916. Serial No. 105,648.

To all whom it may concern:

Be it known that I, ROBERT W. SCHULTZ, a citizen of the United States, residing at Cincinnati, in the county of Hamilton and 5 State of Ohio, have invented certain new and useful Improvements in Spark-Plugs, of which the following is a specification.

My invention relates to ignition devices, and more particularly to an improved spark 10 plug.

The invention has more special reference to an ignition device of the character stated whereby a variable spark may be produced, consequently rendering a construction highly 15 efficient for use in gas engines and the like, and in general, providing a device which will enable the engine to derive a much greater driving power.

More particularly, the present invention 20 has reference to the novel construction of a spark plug, which may be said to comprise a casing carrying a plurality of sparking terminals integrally formed thereupon, a central electrode having a spherical head, 25 which serves as the remaining sparking terminal, the terminals as carried by the casing, being arranged at relatively different distances from the spherical head, thus, affording means whereby a spark of varying 30 lengths and power may be had.

Among the advantages accruing from the novel arrangement of the sparking terminals may be noted, that the varying sparks will prevent the misfiring of the engine under oil 35 flooded conditions; that a poor combustive mixture as delivered from the carburetor will be ignited thereby; also, that the engine will be afforded a much greater "get away power".

40 The annexed drawings and the following description sets forth in detail, certain structures embodying the invention, such disclosed means constituting, however, but one of the various mechanical forms in which 45 the principle of the invention may be used.

In said annexed drawings:—

Figure 1 is a vertical section of my improved spark plug; and

Fig. 2 is a top plan thereof.

50 In detail:—

Referring more particularly to the drawings, wherein like reference characters designate like or corresponding parts throughout the several views, a suitable casing is employed, which I have designated by the numeral 1. The upper portion of this casing

is provided with a shoulder 2 having formed therein an annular recess 3, a portion of which is screw threaded as at 4. The portion of the casing 1 as adjacent the shoulder 2 and indicated by the numeral 5 is of greater thickness than the lower portion thereof and has arranged thereabout screw threads 6, whereby the device may be readily turned into engagement with the cylinder 65 head of the particular engine to which the igniting device is to be applied. Arranged upon the lower marginal edge of the casing 1 and laterally disposed therefrom is a finger 7, which constitutes one of the sparking 70 terminals of my improved device, while arranged adjacent the lower marginal edge of the casing 1 at a point substantially diametrically opposite the electrode 7 and extending toward the latter is a second electrode 8, 75 it being noted that this electrode is of less length than the first mentioned electrode, the purpose of which will be subsequently apparent. This electrode 8 also serves as a sparking terminal. 80

It should be understood from the construction shown in Fig. 1, that the metallic outer body of the spark plug will be constructed of malleable material and consequently the electrodes 7 and 8 of the sleeve 85 1 are bendable to and from the spherical electrode 17 so that the spark gap therebetween can be adjusted. Obviously the length of the sparks between the electrodes 7 and 8 will be governed by the distance to which 90 the electrodes have been bent toward the spherical electrode 17 and by the impressed electro motive force. The manner of securing an adjustment of the sparks is thus simplified as will be obvious from the above explanation and an inspection of Fig. 1 of the drawing. 95

An insulating plug, referred to generally by the numeral 9 is positioned within the casing 1 and has formed thereupon a laterally distended flange 10, also, constructed from insulating material. The upper portion of the insulating plug is of a frustoconical formation and receives upon its upper extremity, a protective cap 11, while the lower portion of the said insulating is reduced, as shown at 12. A longitudinal opening 13 extends around the entire length of 9, and serves to receive an electrode 14, the upper extremity of which is provided with 110 a plurality of screw threads, which I have indicated by the numeral 15, and is adapted

2
to have threaded into engagement therewith, the usual electrical conductor securing nuts 16, while the lower portion of this electrode is provided with a spherical head 17, which head, as is obvious, extends into proximity to the sparking terminals 7 and 8, carried upon the lower marginal edge of the casing.

The flange 10 as formed upon the plug 9 is receivable within the annular recess 3, arranged in the upper portion of the casing 1, the washer 18, being formed of suitable insulating material serving as a resilient seat therefor. To secure the plug in position, an annular locking nut 19 is turned into engagement with the screw threaded portion 4 of the annular recess 3 and binds upon the upper face of the laterally distended flange 10, thus, efficiently maintaining casing and electrodes 13 in proper position for operation.

It will further be noted that the electrode 8 extends from the casing 1 to a point adjacent the side of the spherical head 17, while the electrode 7 extends to a point below this spherical head. Accordingly, when the electrode 14 is rotated in either direction, it is obvious that deposits of carbon will be positively removed from either one or both of these electrodes, since a deposit of carbon on the head 17, when moved from the electrode 7 on one side will not have a support and then coming into engagement with the electrode 8 will be pushed from the head 17. Accordingly, the rotation of the electrode will cause deposits of carbon to be displaced to prevent a short circuiting over the electrodes at the end.

Referring now to the operation of the device as hereinbefore described, current is supplied to the electrodes 7 and 8 and to the electrode 14 in the manner as well known to the art. Should the engine be running at a low rate of speed, the magneto if such is being used, will of course, supply a comparatively small amount of current and consequently the necessary ignition spark will be produced between the electrode 8 and the adjacent portion of the spherical head 17 of the electrode 14, it being noted, that this particular terminal is arranged in closer relation thereto. Should the speed of the engine be increased, and the combustion mixture thereto, necessarily increased, the power as delivered from the magneto will be increased, and a spark will be produced between the electrode 7 and that adjacent portion of the spherical head 17, thus, affording a larger igniting spark. It will be also noted, that as the spark is being produced between the terminal 7 and the spherical head 17, a second spark of less size will be produced between the electrode 8 and its

adjacent portion of the said spherical head 17, consequently, affording an ignition means which will positively ignite even in exceedingly poor mixture and will also prevent the interference with the ignition of the spark under oil flooded conditions.

It should be noted that the longitudinal opening 13 is reduced at its lower portion as at 13', thereby forming an annular shoulder 12'. The electrode 14 is also reduced as indicated at 14', whereby said electrode 14 will rest upon said shoulder. As a consequence the electrode 14 will be supported upon the plug 9 without the aid of secondary securing means, such as the nuts 16, as shown in Fig. 1. As is further noted the electrode may be turned slightly, even though a conductor is secured thereto by the nuts 16, whereby carbon which may collect between the electrodes 7 and 8 and the head 17 may be easily displaced.

Other modes of applying the principle of my invention may be employed, instead of the one explained, change being made as regards the mechanism herein disclosed, provided the means stated by the following claim or the equivalent of said stated means be employed.

I therefore claim as my invention:—

A spark plug comprising a casing, an insulating plug carried upon said casing, said insulating plug having a longitudinally extending bore forward formed therethrough, said bore being reduced adjacent the lower end of said plug, thus forming a shoulder adjacent the lower end of said plug, thus forming a shoulder, an electrode fitting in the reduced portion of said bore, thus causing the electrode to bear upon said shoulder for limiting its movement in one direction, a head formed upon the lower end of said electrode, said head bearing against the lower end of said plug, thus limiting the movement of said electrode, a fixed electrode on said casing extending to a point adjacent the side of said head, a second fixed electrode on said casing extending to a point below said head, wire attaching means mounted upon said first mentioned electrode, said first mentioned electrode being free to rotate, thus causing said head to turn for allowing said fixed electrode to remove deposits of carbon therefrom, while the formation of the reduced portion of said first mentioned electrode will hold said first mentioned electrode against displacement.

In testimony whereof I affix my signature in presence of two witnesses.

ROBERT W. SCHULTZ.
